STEAM IRON

John E. Reed, Glen Ellyn, and Burton Kelly, Bellwood,
Ill., assignors to Sunbeam Corporation, Chicago, Ill., a
corporation of Illinois

Filed Oct. 24, 1962, Ser. No. 72,248

Term of patent 14 years

(Cl. D49—1)

Fig. 3.

Fig. 4.

Fig. 5.

Fig. 6.

FIG. 1 is a front perspective view of a steam iron embodying our new design;

FIG. 2 is a front elevational view thereof;

FIG. 3 is a side perspective view thereof;

FIG. 4 is a rear perspective view thereof;

FIG. 5 is a rear perspective view thereof taken from directly behind and slightly above; and

FIG. 6 is a top plan view thereof.

Our design for the steam iron disclosed is characterized by the handle portion having the configuration as shown in association with the cover and sole plate.

We claim:

The ornamental design for a steam iron, as shown and described.
